BATHING CAP

Thomas J. Howland, Long Branch, N. J.

Application July 30, 1938, Serial No. 222,127

15 Claims.

(Cl. 2-68)

This invention relates to rubber articles of wearing apparel, such as bathing caps, rubber boots, and the like, and is concerned more particularly with a novel article of this character which may be worn with comfort and at the same time is extremely resistant to the seepage of water into the article. The rubber article of my invention is of a simple construction adapted for manufacture at low cost and is substantially waterproof by reason of its inclusion of a novel ribbed structure which prevents the passage of water into the article, even when the article is subjected to severe use.

For illustrative purposes, the principles of the invention will be described and illustrated in connection with a bathing cap, although it will be understood that the invention is not limited to this use but is applicable to other articles of wearing apparel as well.

In bathing caps of the form most commonly used, there is a tendency, when the cap is in use, for water to seep into the interior of the cap between its bottom edge and the head of the wearer, the amount of seepage depending on how tightly the cap fits the head. It has been proposed heretofore to reduce the amount of seepage by providing on the inside of the cap one or more encircling ribs which extend around the cap near its lower edge so as to engage the head of the wearer. These ribs have taken various forms, but in nearly all instances they extend straight inwardly from the cap body and at their free, inner ends are flat, concaved, or convexed. While ribs of this type serve to reduce the amount of seepage, they are not entirely satisfactory for the reason that they have a relatively great resistance to stretching and do not readily bend or incline so as to accommodate the size and the irregularities of the wearer's head, whereby they tend to impair the comfort of the wearer. This is especially so when a pair of parallel encircling ribs are employed which are braced by cross ribs, since the latter add materially to the stiffness of the encircling ribs.

Another form of encircling rib employed heretofore is relatively thin and flexible and projects inwardly a substantial distance from the inner surface of the cap, so that when the cap is applied to the head of the wearer, the rib is forced toward a flat position against the inner surface, whereby only one side of the rib contacts the head. While caps employing an encircling rib of this form are generally more comfortable than those having a relatively stiff rib, they do not

prevent seepage of water into the cap during the normal use thereof.

One feature of the present invention, therefore, resides in the provision of a novel bathing cap which overcomes these objections to prior caps and which is at once comfortable and waterproof to a high degree. A cap made in accordance with my invention comprises a cap body of any desired form made of rubber, or the like, and having at least one rib on the inside of the cap which extends substantially parallel to the edge thereof and preferably encircles the cap. The rib is flexible and may normally extend straight inwardly from the cap body or at an oblique angle thereto, but in either case it is characterized in that it terminates at its free end in a thin edge located on one side of its center line. Thus, when the cap is put on, the off-center edge is the first part of the rib to engage the head of the wearer, and by reason of its thinness it is upset in the direction in which it is off center and causes the rib to deflect in that direction. Accordingly, the rib readily adapts itself to the contour of the head by deflecting more or less under the action of the off-center edge. However, the main body of the rib is sufficiently stiff to prevent the rib from upsetting completely and maintains the deflected end of the rib firmly against the head.

In the preferred construction, the rib is provided with at least one fin located near its free end on the opposite side of the center line from the thin contacting edge. With this construction, the contacting edge when deflected causes the fin to engage the head so that the fin and the contacting edge form between them a recess which becomes in effect a suction cup. Accordingly, the cap not only affords comfort to the wearer by reason of the deflection of the contacting edge of the rib, but also is extremely resistant to the entrance of water into the cap because of the suction cup or recess between the contacting edge and the fin.

Another feature of the invention resides in the provision of a bathing cap having a pair of encircling ribs and novel means for biasing the ribs against the head of the wearer. I have found that by providing ribs extending generally transversely to the encircling ribs and on the outside of the rubber or other material which supports the encircling ribs, the cap when stretched on the head of the wearer assumes a convex form on the outside between the encircling ribs, thereby forcing the latter inwardly against the head. Since the transverse ribs are

spaced apart and are relatively narrow, they do not interfere with the stretching of the edge portion of the cap when it is applied to the head and therefore do not impair the comfort of the wearer. The transverse ribs may take various forms and may extend at right angles to the encircling ribs or may be inclined at an acute angle thereto, although I have found that the biasing action on the encircling ribs is more pronounced when the transverse ribs are at right angles to the encircling ribs.

These and other features of the invention may be better understood by reference to the accompanying drawing, in which

15 Fig. 1 is a side view of one form of a new bathing cap made in accordance with the invention;

Fig. 2 is a section through part of the cap shown in Fig. 1;

20 Fig. 3 is an enlarged detail view showing a section of the encircling ribs;

Fig. 4 is a section on line 4—4 in Fig. 3;

Figs. 5 to 13, inclusive, are cross sections through modified forms of encircling ribs, showing the ribs applied to a cap body; and

25 Fig. 14 is an enlarged cross section through the ribs shown in Fig. 3, illustrating the action of the ribs when the cap is being used.

Referring to the drawing, the numeral 20 designates a bathing cap of any desired form comprising a hollow body 21 made of rubber, or the like, the body being shaped to fit the general contour of the head. Along the inside edge of the body 21 is attached a rubber cup band comprising a base 22 and two pairs of spaced, parallel 30 encircling ribs 23, the ribs extending generally parallel to the edge of the cap. Between each pair of encircling ribs are a plurality of cross or bracing ribs 24 which extend at oblique angles to the encircling ribs in zig-zag fashion, as shown 35 in Fig. 3. The cross ribs 24 serve to brace the encircling ribs and tend to prevent them from being bent against the cap body 21 when the cap is worn.

The uppermost encircling rib 23 extends inwardly from the cap body at right angles thereto, as shown in Fig. 4, and terminates at its free end in a thin edge 25 located on the upper side of the center line of the rib. On the opposite side of the center line, the rib is formed with a fin 26 which terminates inwardly toward the base 22 from the off-center edge 25. The free end of rib 23 is concaved between the off-center edge 25 and the center line, as shown at 27, and between the concave portion 27 and fin 26, the rib is formed with a relatively deep recess or groove 28. The rib 23 directly below the uppermost encircling rib terminates at its free end in a thin edge 25' located on the lower side of its center line and is formed with a fin 26' located 40 on the opposite side of the center line and disposed inwardly toward the base 22 from the off-center edge 25'. The free end of the rib is concaved between the off-center edge 25' and the center line, as shown at 27', and is formed 45 with a groove 28' between the concave portion and the fin 26'.

The two encircling ribs 23 near the lower edge of the cap are identical with the uppermost pair and need not be described in detail.

50 When the cap is worn, the head 29 of the wearer is engaged by the free ends of the encircling ribs 23, as shown in Fig. 14. More particularly, the thin contacting edges 25 and 25' are the parts of the ribs which first engage the head of the wearer, and by reason of the thin-

ness of each of these edges and its off-center location on the rib, it is deflected by the head 29 in the direction in which it is off center. That is, the edge 25 of the uppermost encircling rib is deflected upwardly, as shown in Fig. 14, and causes the concave portion 27 and the fin 26 of the rib to engage the head. The encircling rib immediately below the uppermost rib 23 is bent downwardly, however, since its thin, contacting edge 25' is on the lower side of its center line. As a result of the bending of the ends of the ribs in opposite directions, some of the air is forced out of the pockets or cups formed by the encircling ribs and the cross ribs 24, and the suction effect of the cups tends to maintain the engagement of the edge of the cap with the skin and prevent the cap from being pulled off the head. Similarly, the bottom rib 23 is bent downwardly at its end, and the rib immediately above it is bent upwardly. This tendency of the two pairs of ribs to deflect away from each other is opposed by the cross ribs 24 which lend a certain degree of stiffness to the body of the ribs, so that only the end portions are substantially deflected. It will be observed that in 55 the deflected positions of the ribs, the fins contact the head of the wearer on one side of the ribs while the off-center edges contact the head on the other side, and the inside edges of the concave portions 27 and 27' contact the head 30 between the fins and the off-center edges. Accordingly, each rib forms at its free end two suction recesses, one being formed by the concaved portion 27 or 27' and the other by the groove 28 or 28'. The plurality of suction 35 recesses thus formed serve in effect to supplement the action of the main suction cups formed by the encircling ribs themselves and by the cross ribs 24, as will be readily understood.

With this construction, the free end portions 40 of the encircling ribs are deflected more or less, depending on the pressure exerted by the cap on the head of the wearer, whereby the cap may readily accommodate itself to the contour of the head. By reason of the thin, off-center edges 45 at the free ends of the ribs, the latter are always deflected in such a manner that each rib is biased away from the opposite rib with which it is paired, and because of this deflection the fins 26 and 26' are caused to positively engage 50 the head of the wearer and form the two suction recesses referred to. Thus, the cap is not only comfortable to the wearer, but is extremely 55 resistant to the entrance of water into the cap under the bottom edge thereof.

In order to render the encircling ribs still more effective to resist the seepage of water into the cap, I prefer to provide on the outside of the cap a plurality of flexible ribs 30 extending transversely of the encircling ribs. The ribs 30 are 60 spaced apart along the edge of the cap, as shown in Fig. 1, and are of a length equal approximately to the width of the cup band 22, the ends of the ribs 30 coinciding with the edges of the cup band. Preferably, at each of the ear portions of the cap the ribs 30 are omitted and a pair of relatively long ribs 32 are cemented or molded on the outside of the cap. The ribs 32, as shown, are substantially twice as long as the ribs 30 and extend upwardly in slightly diverging 65 relation from the edge of the cap. On the inside of the cap at each of the ear portions is a pair of base members 33 made of sponge rubber, or the like, the base members being positioned 70

to contact the head of the wearer on opposite sides of the ear near the top thereof.

When the cup band 22 is stretched on the head of the wearer, the outer ribs 30 cause the outside of the cap over the cup band to assume a convex form, as shown in Fig. 14, whereby the uppermost and lowermost encircling ribs 23 are pressed or biased with a greater force against the head than the two intermediate ribs. I have found that this action is to great advantage in preventing the seepage of water into the cap, because it augments the sealing effect of the uppermost and lowermost encircling ribs and helps to prevent the admission of air into the cup band, whereby the suction effect of the band cups is better preserved when the cap is subjected to severe use.

The ribs 30 may take various forms and they may be arranged to extend either at right angles to the encircling ribs or at acute angles thereto. However, I have found that the biasing action afforded by them is more pronounced when they are arranged at right angles to the encircling ribs. The ribs 32 on the ear portions of the cap have a similar effect when the edge of the cap is stretched, in that they cause the parts of the cap overlying the ears to assume a convex form on the outside, so that the parts of the cap immediately above and below the ear contact the head with a greater force and more effectively resist the seepage of water into the cap around the ears. The base members 33 serve to absorb the stress which would otherwise be exerted on the ears by the ribs 32 due to their biasing action, and also permit the ribs 32 to act more readily under the stretching action of the material of the cap.

The ribs 30 are shown as cemented on the outside of the cap body, but it will be apparent that they may be formed by molding them in the operation of making the cap body. Also, the ribs 30, instead of being positioned on the outside of the cap body, may be located between the cap body and the cup band 22 so that they are covered by the cap body, although when the latter construction is used, the cup band should be somewhat heavier than the material of the cap body. The larger ribs 32 may also take different forms. For example, the upper ends of the ribs 50 may be joined so that the ribs form a figure similar to a horse shoe. I have found that when the ribs are arranged in such a figure, they do not press the part of the cap directly above the ears against the head because of the horizontal rib joining them at the top, but the ribs act to press the lower edge of the cap against the head below the ears and thereby prevent seepage of water into the ear portions of the cap.

While I have shown a cup band 22 inside the cap having four encircling ribs, it will be understood that only one encircling rib, or any other number, may be employed, although I prefer to use at least a pair of encircling ribs so as to form suction cups between them which are biased by the outside ribs 30. The cross ribs 24 may be straight or concave at their free ends, instead of convex as shown, and may be arranged to form suction cups which are diamond-shaped, square, oval, etc., instead of triangular. Also, the cup band 22 may vary in form from that shown in Figs. 3 and 4, and I have illustrated in Figs. 5 to 13, inclusive, several other forms of cup bands which may be employed, all of which embody the principles of my invention.

Referring to Fig. 5, the cup band there shown

comprises a pair of encircling ribs 35 diverging from the base of the band and joined by cross ribs 36, arranged in any desired manner. The upper rib 35 terminates in a thin edge disposed above the center line of the rib, while the lower rib terminates in a thin edge disposed below the center line of the rib. At their free ends, the ribs 35 are concaved, as shown at 37, so as to form fin-like projections 38 on the opposite sides of the ribs from the thin, off-center edges, the projections 38 being adapted to contact the head of the wearer when the thin off-center edges of the ribs are upset. The free ends of the cross ribs 36 may likewise be concaved.

The cup band shown in Fig. 6 comprises a pair of encircling ribs 40 which project at right angles to the base of the cup band and terminate at their free ends in thin edges 41 located on the lower side of the center lines of the ribs. On the opposite side of the center lines, the ribs are formed with fins 42 adapted to engage the head of the wearer after the thin, contacting edges 41 are upset downwardly by the head. Each of the ribs 40 is braced by a series of transverse ribs 43 on the upper side of the encircling rib.

The cup band shown in Fig. 7 comprises a pair of encircling ribs 45 diverging from the base of the cup band and terminating at their free ends in thin edges 46. The edge 46 of the upper encircling rib is located above the center line of the upper rib, while the edge 46 of the lower encircling rib is located below the center line of the lower rib. The free ends of the ribs 45 are of convex form, as shown at 47, and the free ends of the cross ribs 48 are also convex.

Referring to Fig. 8, the cup band there shown comprises a single encircling rib 50 which in cross section is of the general form of a right triangle, the base of the triangle being adjacent the base of the cup band. Thus, the peak 51 of the rib 50 forms a thin contacting edge which is located below the center line of the rib. On its inclined side the rib 50 is formed with a fin 52 which is adapted to engage the head of the wearer when the edge 51 is deflected downwardly by the head.

In the cup band shown in Fig. 9, the base is provided with an encircling rib 54 which is enlarged at its base, the rib tapering from the base and then expanding into an enlargement at the free end of the rib. At its free end, the rib is formed with a thin edge 55 disposed below the center line of the rib, and from the edge 55 the enlargement of the rib is inclined inwardly toward the base. On the inclined part of the enlargement, the rib is formed with a pair of spaced fins 56 and 57 which engage the head of the wearer after the thin edge 55 is bent downwardly.

The cup band shown in Fig. 10 comprises an encircling rib 59 which normally extends obliquely downwardly from the base of the band and tapers to a thin edge 60. On the side of the rib remote from the cap body is a pair of spaced fins 61 and 62, and on the base of the cup band is a rib 63 adapted to engage the opposite side of the main rib 59. When the rib 59 is contacted by the head of the wearer, it is deflected downwardly against the rib 63, so that the fins 61 and 62 contact the head.

In Fig. 11, I have shown a cup band comprising a relatively thick rib 65 having an enlarged base adjacent the base of the band. The rib 65 tapers from its base to a point about midway between its end and then expands into an enlargement which includes three symmetrical fins 66, 76

67 and 68 adapted to engage the head of the wearer.

The cup band shown in Fig. 12 comprises a base 70 secured along its lower edge to the inside of the cap body near the edge of the latter. On the side of the base 70 remote from the cap body are three encircling ribs 71 extending lengthwise of the base and spaced apart. Each of the ribs terminates at its free end in a thin edge 72 located on one side of the center line of the rib, the edge 72 of the uppermost rib being above the center line and the edge 72 of the lower rib being below the center line. Each rib is formed on the opposite side of its center line with a fin 73 which terminates inwardly toward the base 70 from the off-center edge and is adapted to contact the head of the wearer when the off-center edge is deflected. On the side of the base 70 adjacent the cap body is a series of spaced ribs 74 which may be formed in the molding operation in which the cup band is made. The ribs extend generally transversely of the encircling ribs 71 and are relatively thick at the center but taper towards the ends. When the band 70 is stretched on the head of the wearer, the ribs 74 cause the side of the band remote from the cap body to assume a concave form, whereby the uppermost and lowermost ribs 71 are pressed against the head with a greater force than the intermediate rib 71. While the additional pressure thus exerted on the uppermost and lowermost encircling ribs is effective in increasing the sealing effect of the latter, it does not impair the comfort of the wearer in any way, because the thin off-center edges 72 of the ribs are upset by the head of the wearer and tend to cushion the additional pressure. By reason of the edge connection of the base of the cup band with the cap body, the cup band may readily adjust itself to irregularities of the head. It will be apparent that the cup band, if desired, may be connected to the cap body along its upper edge, instead of its lower edge.

The cup band shown in Fig. 13 comprises a base 76 which is normally convex on its outside and concave on its inside, the base being connected at its central portion to the cap body by a connection 77. On its concave side, the base 76 is provided with three encircling ribs 78 which are of substantially equal length, whereby the uppermost and lowermost ribs project further inwardly than the intermediate rib because of the concavity of the base. Each of the ribs 78 terminates at its free end in a thin edge 79 located on one side of the center line of the rib, the edge 79 of the uppermost rib being above the center line and the edge 79 of the lowermost rib being below the center line. The encircling ribs are preferably braced by cross ribs 81. When the cap is applied to the head, the base 76, by reason of its concave form, maintains the uppermost and lowermost ribs 78 against the head with a greater pressure than the intermediate rib, so as to prevent more effectively any seepage of water between the skin and the free ends of the encircling ribs. Since the base 76 of the cup band is connected only at its central portion to the cap body, the cup band may readily adapt itself to irregularities of the head.

It will be understood that the cross ribs may take other forms and may be disposed in other arrangements than those illustrated. For example, they may extend at right angles to the encircling ribs or at oblique angles thereto in zig-zag fashion. Also, they may extend only partly across the space between the encircling

ribs or, instead of projecting into this space, they may extend from the side of the encircling rib remote from the adjacent encircling rib. The term "fin" as used herein is intended to denote any protruding edge, sharp or rounded, formed by two intersecting surfaces. The term "neutral" as applied to the outer ribs 32 is intended to denote unstressed ribs, that is, ribs which are subjected to neither tension nor compression.

I claim:

1. A bathing cap comprising an elastic cap body, and a pair of elastic ribs on the inside of the cap body extending generally parallel to the edge thereof, the lower rib terminating at its free end in a thin, initial skin-contacting edge located on the lower side of the center line of the lower rib, and the upper rib terminating at its free end in a thin, initial skin-contacting edge located on the upper side of the center line of the upper rib.

2. A bathing cap comprising an elastic cap body, a pair of elastic ribs on the inside of the cap body extending generally parallel to the edge thereof, the lower rib terminating at its free end in a thin, initial skin-contacting edge located on the lower side of the center line of the lower rib, and the upper rib terminating at its free end in a thin, initial skin-contacting edge located on the upper side of the center line of the upper rib, cross ribs extending between the first ribs for bracing them, and fins on said first ribs located at the adjacent sides thereof in opposed relation and terminating short of the respective initial skin-contacting edges.

3. A bathing cap comprising an elastic cap body, and an elastic rib on the inside of the cap body extending generally parallel to the edge thereof and terminating at its free end in a thin, initial skin-contacting edge located on one side of the center line of the rib, the free end of the rib being concaved between said off-center edge and center line, the rib having a fin on the opposite side of said center line terminating short of said free end and a relatively deep groove between said concave portion and the fin.

4. In a bathing cap, a pair of elastic ribs located on the inside of the cap body and extending generally parallel to the edge thereof, said ribs diverging from the cap body and each terminating at its free end in a thin, initial skin-contacting edge disposed on the side of the center line of the rib opposite the other rib, the free end portion of each rib being inclined sharply from said thin edge toward the cap body and having a substantial concavity, and cross ribs extending between said first ribs for bracing them.

5. In a bathing cap, an elastic rib located on the inside of the cap body and extending generally parallel to the edge thereof, said rib having a cross section in the general form of a right triangle with the base thereof adjacent the cap body, and a fin on the inclined side of the rib.

6. An article of wearing apparel comprising a hollow elastic body having an opening therein, a pair of ribs on the inside of the body extending generally parallel to the edge of the opening and spaced apart, and a plurality of ribs on the outside of the body near the edge of the opening, said last ribs being spaced along said edge generally transversely of the first ribs, and said first ribs being disposed substantially opposite the ends of said transverse ribs, whereby the transverse ribs force said first ribs inwardly when said edge portion of the body is stretched.

7. An article of wearing apparel comprising a hollow elastic body having an opening therein, an elastic band on the inside of the body extending generally parallel to the edge of the opening, a pair of ribs on the side of the band remote from the body and extending generally parallel to the band near the side edges thereof, and a plurality of ribs disposed outwardly of the band near the edge of the opening, said last ribs being spaced along said edge and extending generally transversely of the band with the ends thereof substantially coinciding with the side edges of the band, whereby the transverse ribs force said first ribs inwardly when the edge of the body around said opening is stretched.

8. A bathing cap comprising an elastic cap body having normally flat ear-engaging portions adapted to completely cover the wearer's ears and lying flush with the adjacent side walls of the cap body, a pair of ribs on the outside of the body over each of the ear portions, each pair of ribs extending upwardly from the edge of the cap body in spaced relation and terminating near the part of the cap under which the top of the wearer's ears normally lie, said ribs being operable to force the lower edge portions of the cap body under the ears inwardly against the head of the wearer when the edge portion is stretched on the head, and inwardly projecting base members on the inside of the cap body disposed only near the upper ends of said ribs for holding the adjacent parts of the cap body away from the head of the wearer to permit said ribs to act freely on the edge portion of the cap.

9. A bathing cap comprising a cap body, a pair of ribs on the inside of the cap body extending substantially parallel to the edge thereof and spaced apart, said ribs extending inwardly from the cap body in diverging relation, and cross ribs extending between said first ribs for bracing them.

10. In an article of apparel comprising a hollow body having an opening therein, an elastic rib on the inside of the body extending generally parallel to the margin of the opening and projecting inwardly from the body with its free end terminating in a thin, initial skin-contacting edge located on one side of the center line of the rib, the rib having a fin offset laterally from said edge and terminating short of the edge, the rib being flexible and readily deflectable laterally, whereby said edge when pressed against the skin is upset laterally in the direction in which it is off-center and tilts the rib in said direction to cause the fin to contact the skin.

11. In an article of apparel comprising a hollow body having an opening therein, an elastic rib on the inside of the body extending generally parallel to the margin of the opening and projecting inwardly from the body with its free end terminating in a thin, initial skin-contacting edge located on one side of the center line of the rib, the rib having a fin on the opposite side of the center line terminating short of said edge and also having a recess between the fin and said edge, the rib being flexible and readily deflectable laterally, whereby said edge when pressed against the skin is upset laterally in the direction in

which it is off-center and tilts the rib in said direction to cause the fin to contact the skin.

12. In an article of apparel comprising a hollow body having an opening therein, an elastic rib on the inside of the body extending generally parallel to the margin of the opening and projecting inwardly from the body with its free end terminating in a thin, initial skin-contacting edge located on one side of the center line of the rib, the free end portion of the rib being inclined sharply inwardly from said off-center edge toward the body, the rib being flexible and readily deflectable laterally, whereby said edge when pressed against the skin is upset laterally in the direction in which it is off-center and tilts the rib in said direction to cause said inclined free end portion to contact the skin.

13. An article of apparel comprising a hollow body having an opening therein and an elastic portion around the opening, a plurality of spaced ribs on the outside of said portion extending generally transversely thereof, the ribs terminating at their lower ends adjacent the lower edge of said portion and extending upwardly a substantial distance therefrom, and a rib on the inside of the body extending generally parallel to said portion and disposed substantially opposite the upper ends of the outer ribs, said outer ribs being operable to force the inside rib and the lower edge of said portion inwardly when said portion is stretched.

14. A bathing cap comprising an elastic cap body having normally flat ear-engaging portions adapted to completely cover the wearer's ears and lying flush with the adjacent side walls of the cap body, a rib inside the body extending generally parallel to the edge thereof and along the sides of the cap, and a pair of normally neutral ribs on the outside of the body over each of the ear portions, each pair of said outer ribs extending upwardly from the edge of the cap body in spaced relation and terminating a substantial distance above said inner rib and near the part of the cap under which the top of the wearer's ear normally lies, said outer ribs being operable to force the upper and lower boundaries of said ear portions inwardly against the head of the wearer with a greater force than the inner rib and the parts of said ear portions between said boundaries when the edge portion of the cap is stretched on the head.

15. An article of apparel comprising a hollow body having an opening therein and an elastic portion around the opening, a plurality of normally neutral, spaced ribs on the outside of the elastic portion extending generally transversely thereof, the ribs terminating at their lower ends adjacent the lower edge of the elastic portion and extending upwardly a substantial distance therefrom, and a rib on the inside of the body extending generally parallel to said portion and disposed substantially opposite the lower ends of the outer ribs, the outer ribs being operable to force the inside rib and the part of said elastic portion adjacent the upper ends of the outer ribs inwardly with a greater force than the region of said portion between the inside rib and said part when the elastic portion is stretched.

THOMAS J. HOWLAND.
